VECTOR SOLVER

John J. Reza, Vallejo, Calif.

Application May 16, 1945, Serial No. 594,135

3 Claims. (Cl. 33—76)

(Granted under the act of March 3, 1883, as
amended April 30, 1928; 370 O. G. 757)

1

This invention relates to a vector solver and more particularly to a device for performing vectorial addition.

A vector or a vectorial quantity may be defined as a quantity that has both magnitude and direction. Examples of such quantities are forces or velocities. It frequently is necessary to add vectorially a plurality of vectors and thus to obtain the magnitude and direction of the resultant vector.

It is the principal object of the present invention to provide a device that enables a user to determine expeditiously and accurately the magnitude and direction of the resultant of a plurality of vectors or vectorial quantities.

It is a further object of the invention to provide for accomplishing the above object in an economical, facile and efficient manner.

In accomplishing these and other objects of the present invention, I have provided improved details of structure, the preferred form of which is illustrated in the accompanying drawing, wherein:

Fig. 1 is a top plan view of a vector solver embodying my invention.

Fig. 2 is a vertical sectional view of the vector solver taken substantially on the line 2—2, Fig. 1.

Fig. 3 is a vertical sectional view of a detail of the vector solver taken substantially on the line 3—3, Fig. 1.

Referring more in detail to the drawing:

The device of my invention comprises a base plate 1. Guide slots 2, 3, and 4 are cut into the upper face of the plate 1. The guide slots are preferably of inverted T-shaped cross section, Fig. 2. The plate 1 also has a central opening 5 that is substantially circular in configuration. An angular scale 6 is engraved or otherwise suitably marked on the plate 1 surrounding the opening 5.

A guided element 7 is provided and is adapted to be fitted within any one of the slots 2, 3, or 4. The guided element 7 is preferably T-shaped in cross section, Fig. 2, to fit within the T-shaped slots 2, 3, or 4. One or more screws 8 and 9 are threaded through the guided element 7 and bear against the upper face of the bottom of a slot 2, 3, or 4 to enable the guided element 7 to be held in adjusted position in the slots.

An arm 10 is pivoted to the guided element 7 by means of the screw 11. The screw 11 may be tightened to hold the arm 10 in angularly adjusted position with respect to the guided element 7.

The arm 10 supports a linear scale member

2

12 which is longitudinally slidable thereon. The arm 10 has a longitudinal slot 13 extending substantially the length thereof. A bolt 14 extends through the slot 13 and through an aperture in the member 12. A nut 15 on the bolt 14 enables the member 12 to be held securely in longitudinally adjusted position with respect to the arm 10. The member 12 has a pair of scales 16 engraved or otherwise suitably marked thereon adjacent its longitudinal edges. Preferably, the longitudinal edges are beveled so that the scales 16 are in close contact with the other scales.

Fitted within the circular opening 5 in the base plate 1 is a substantially circular disc 17, which is freely rotatable in the opening 5. A plurality of linear scales 18 are engraved or otherwise suitably marked on the upper face of the disc 17 on radii of the disc. I prefer to provide four such linear scales 18 on perpendicular diameters of the disc 17.

To facilitate rotation of the disc 17, I provide a series of finger grips 19 in the upper face of the disc, preferably in locations in which they do not interfere with the scales 18.

25 In order to prevent undesired rotation of the disc 17, I provide a spring braking device 20 in the base plate 1. The braking device comprises a plunger 21 and a spring 22. Normally the inner end of the plunger 21 is held in contact with the side edge of the disc 17 and the friction therebetween prevents undesired rotation. When it is desired to rotate the disc 17, the plunger 21 is held outwardly out of contact with this disc, and the disc is then freely rotatable.

Operation

When it is desired to add a plurality of vectorial quantities and thus to obtain the magnitude and direction of the resultant thereof, the process may be accomplished by use of my device in the following manner:

(a) The disc 17 is rotated until one of the scales 18 is aligned with the angle indicated on the scale 6 that corresponds with the direction of the prime vector.

(b) The guided element 7 is inserted within the appropriate slot 2, 3, or 4. The guided element 7 is adjusted longitudinally of the slot and the arm 10 and linear scale member 12 are pivoted about the screw 11 until one of the edges of the member 12 passes through the center of the disc 17 and through the angle on the scale 6 corresponding with the direction of the second vector. The screw 11 is then tightened to hold the arm 10 and member 12 in angularly adjusted position.

(c) The guided element 7 is adjusted within the slot 2, 3, or 4 and the member 12 is adjusted longitudinally of the arm 10 until the origin of the scale 16 is at the point on the scale 18 that corresponds with the magnitude of the prime vector, angular adjustment of the arm 10 on the guided element 7 being kept constant.

(d) The disc 17 is rotated until the point on the scale 16 representing the magnitude of the second vector is crossed by one of the scales 18.

(e) The magnitude of the resultant of the two vectors is represented by the distance on the scale 18 between the center point of the disc and the point at which the scale 18 crosses the scale 16. The direction of the resultant is the direction of the scale 18 as indicated on the angular scale 6.

It is apparent that through use of the device it is possible to add or subtract any number of vectors in the manner described; that is, any two of the vectors may be added or subtracted in the manner described and the subsequent vectors may be added or subtracted to the resultant obtained in the first operation.

While I have shown but one embodiment of my invention, it is apparent that the device is susceptible to modification without departing from the spirit of the invention. I do not wish, therefore, to be limited by the disclosure set forth, but only by the scope of the appended claims.

The invention described herein may be manufactured and used by or for the Government of the United States of America for governmental purposes without the payment of any royalties thereon or therefor.

I claim:

1. In a device of the character described, a base plate having at least one slot and a substantially circular central opening in the upper face thereof and having an angular scale surrounding said central opening, a substantially circular disc fitted into said opening and being freely rotatable therein about the center of said angular scale and having at least one radial linear scale on the upper face thereof, whereby said linear scale may be rotated to any desired angle with respect to said angular scale, braking means to prevent undesired rotation of said disc, a guided element slidably mounted in said slot, an arm pivotally mounted on said guided element, and a member having a second linear scale slidably mounted on said arm, whereby the origin of said second

linear scale may be placed over any point on said first linear scale and at any desired angle thereto.

2. In a device of the character described, a base plate having slots and an angular scale on its upper face, a substantially circular disc having radial linear scales on the upper face thereof rotatably mounted on said base plate to pivot about the center of said angular scale, whereby any one of said linear scales may be rotated to any desired angle with respect to said angular scale, a guide slidably mounted in one of said slots, an arm pivotally mounted on said guide, and a member having a second linear scale slidably mounted on said arm, whereby the origin of said second linear scale may be placed over any point on said first linear scale and at any desired angle thereto.

3. In a device of the character described, a base plate having a pair of spaced parallel slots and having a third slot crossing said parallel slots perpendicularly adjacent an end of each of said parallel slots so as to define a generally U-shaped design on said base plate, said base plate having a substantially circular recess in the upper face thereof approximately centrally located within said U-shaped design, an angular scale surrounding said central recess, a substantially circular disc fitted into said recess and being freely rotatable therein about the center of said angular scale and having at least one radial linear scale on the upper face thereof, whereby said linear scale may be rotated to any desired angle with respect to said angular scale, braking means to prevent undesired rotation of said disc, a guided element adapted to be slidably mounted in any one of said slots, an arm pivotally mounted on said guided element, and a member having a second linear scale slidably mounted on said arm, whereby the origin of said second linear scale may be placed over any point on said first linear scale and at any desired angle thereto.

JOHN J. REZA.
